[57] CLAIM

The ornamental design for a step for vehicle, as shown and described.

DESCRIPTION

FIG. 1 is a perspective view of a step for vehicle showing our new design;

FIG. 2 is a front elevational view of the step for vehicle of our new design;

FIG. 3 is a top plan view thereof;

FIG. 4 is bottom plan view thereof;

FIG. 5 is rear elevational view thereof;

FIG. 6 is a side elevational view taken along the lines 6—6 of FIG. 2;

FIG. 7 is a side elevational view taken along the lines 7—7 of FIG. 2; and,

FIG. 8 is a perspective view of the step for vehicle showing our new design, it being understood that the broken lines are for illustrative purposes only, to illustrate the environment in which the step for vehicle will be used, with such forming no part of the claimed design.

FIG. 1

FIG. 2

FIG. 3

FIG. 4

FIG. 5
